UNITED STATES PATENT OFFICE.

HENRY W. KNAUTZ, OF CHICAGO, ILLINOIS.

DISPLAY DEVICE.

1,011,447.

Specification of Letters Patent. Patented Dec. 12, 1911.

Application filed February 6, 1911. Serial No. 606,818.

To all whom it may concern:

Be it known that I, HENRY W. KNAUTZ, a citizen of the United States, and a resident of the city of Chicago, county of Cook, and 5 State of Illinois, have invented certain new and useful Improvements in Display Devices, of which the following is a specification.

My invention relates to improvements in 10 display devices and more specifically to that class thereof which are designed for employment especially in the displaying of cloth samples or other similar articles which may be secured or mounted upon cards for 15 purposes of display.

The object of my invention is the production of a display device of the character mentioned in which the display cards will be so connected or bound together as to be 20 adapted to be readily and easily disconnected or interchanged if desired.

A further object is the provision of a display device of the character mentioned which will be of durable and economical 25 construction and of great efficiency in use.

Other objects will appear hereinafter.

With these objects in view my invention consists in the combinations and arrangements of parts hereinafter described and 30 claimed.

My invention will be more readily understood by reference to the accompanying drawing forming a part of this specification and in which,

35 Figure 1 is a plan view of a display device embodying my invention, the same being shown in open condition, Fig. 2 is a section taken on line $x-x$ of Fig. 1, Fig. 3 is a plan view of one of the sections of the device 40 detached, and Fig. 4 is a section taken on line $y-y$ of Fig. 3.

Referring now to the drawing 1 indicates the display cards upon which the samples or other articles are suitably arranged and secured for display. The cards 1 are preferably of rectangular form, and all are of substantially the same dimensions.

Secured to the rearward edge 2 of each of the cards 1 is a narrow elongated strip 3, 50 the same being hingedly secured thereto by means of a hinged strip 4 formed preferably of fabric. The strip 3 is of a length substantially equal to that of the edge 2 and the same is formed of a suitable material 55 possessing rigidity, such for example as card board, which is preferably employed. Ar-

ranged upon each of the cards 1 at the respective extremities of the edge 2 thereof are inwardly opening pockets 5, the same being formed preferably integrally with the 60 hinged members 4. In order to accommodate said pockets the upper and lower edges of each of said cards 1 are notched as at 6, such provision, as will be observed, affording clearance for the adjacent end walls of 65 said pockets. Said pockets are of a width substantially equal to that of the strips 3, the latter being adapted to snugly engage the same.

With the arrangement as set forth it is 70 apparent that any number of cards 1 may be connected together in book form, the connection of adjacent of said cards being effected by engaging the extremities of the strip 3 on an upper card with the pockets 5 of a 75 lower one, as clearly shown in Fig. 1, it being clear, that in effecting such engagement it is necessary to buckle the strip 3 in order to reduce the length thereof sufficient to permit of its extremities engaging said 80 pockets. Upon releasing the strip after buckling and with its extremities registering with the pockets 5, said extremities, upon the strip, assuming its normal condition, will be forced into engagement with said pockets. 85 Then the upper card is laid over the lower one, member 4 bending to permit this, and the pocket on the under side of said upper card is exposed for the reception of the strip of the next upper card. Thus it will be 90 seen that any number of display cards may be connected together in book form with ease and expedition. Also said cards after being connected may be readily and quickly interchanged or re-arranged if desired so as 95 to produce a better arrangement of the samples or articles carried thereby for displaying purposes.

A display device of a construction as described is simple and economical and hence 100 may be manufactured at a low cost.

While I have illustrated and described the preferred form of my invention I do not wish to be limited thereto but desire to avail myself of such variations and modifications 105 as come within the scope of the appended claims.

Having described my invention what I deem as new and desire to secure by Letters Patent is:

1. A display device comprising a plurality of separate cards; strips flexibly and detach-

ably secured to each of said cards; and means on each of said cards for detachably engaging the strip on another card, substantially as described.

5 2. A display device comprising a plurality of separate cards, each provided with transversely alining notches in its edges near one end; and flexible strips each provided at opposite sides at one end with inwardly opening pockets adapted to engage the notches and edges of a card and at the other

end with a strip adapted to engage a pocket engaging another card, substantially as described.

In testimony whereof I have signed my name to this specification in the presence of two subscribing witnesses.

HENRY W. KNAUTZ.
